UNITED STATES PATENT OFFICE.

CHARLES C. WHITTAKER, OF WILKINSBURG, PENNSYLVANIA, ASSIGNOR TO WESTINGHOUSE ELECTRIC AND MANUFACTURING COMPANY, A CORPORATION OF PENNSYLVANIA.

CONTROL APPARATUS.

1,347,880.

Specification of Letters Patent. Patented July 27, 1920.

Application filed December 2, 1916. Serial No. 134,762.

To all whom it may concern:

Be it known that I, CHARLES C. WHITTAKER, a citizen of the United States, and a resident of Wilkinsburg, in the county of Allegheny and State of Pennsylvania, have invented a new and useful Improvement in Control Apparatus, of which the following is a specification.

My invention relates to control apparatus and especially to certain structural features of liquid rheostats and the like.

In a copending application of A. J. Hall, Serial No. 101,960, filed June 6, 1916, and assigned to the Westinghouse Electric & Manufacturing Company, is shown and described an inlet weir of general tubular form for liquid rheostats that is adapted to receive liquid at one end and discharge it through a side opening, the liquid following a spiral path of admittance to the rheostat proper.

It is the object of my present invention to improve certain structural features of an inlet weir of the above-indicated class, whereby a substantially equal efflux of liquid obtains throughout the width of the rheostat.

A further object of my invention is to provide a relatively compact rugged and durable unitary structure for the purpose under consideration which may be readily installed or removed.

My invention may best be understood by reference to the accompanying drawings, wherein Figure 1 is a plan view, with parts broken away for clearness, of a liquid rheostat tank embodying my inlet weir; Fig. 2 is a sectional view taken on the line II-II of Fig. 1; and Fig. 3 is a simplified perspective view of a modification of my invention.

Referring to Fig. 1 and Fig. 2 of the drawing, the structure shown comprises a rectangular liquid rheostat tank 1 of any suitable material having an inlet pipe 2 communicating with the tank near one lower corner thereof, as shown in Fig. 2; an inlet weir 3 for receiving liquid from the pipe 2 and of a novel construction to be described; a plurality of plates or electrodes 4 and barrier members 5 of insulating material that are severally positioned substantially at right angles to the longitudinal dimension of the inlet weir 3; and a plurality of

discharge openings 6 that are located at the opposite end of the tank from the inlet weir 3.

The tank member 1, electrodes 4, insulating barriers 5 and discharge openings 6 constitute no part of my present invention, except in so far as they perform a necessary function in connection therewith, and, consequently, no detailed description thereof is believed to be necessary. The recited parts are fully set forth and claimed in copending applications of A. J. Hall, Serial Nos. 134,304 and 138,004, filed Dec. 1, 1916, and Dec. 20, 1916, respectively, and in another copending application of A. J. Hall and C. C. Whittaker, Serial No. 136,033, filed Dec. 9, 1916, all assigned to the Westinghouse Electric & Manufacturing Company, to which reference may be made for further description.

The preferred general arrangement of parts of the liquid rheostat may be briefly set forth as follows: Liquid enters through the pipe 2 from any suitable continuous-circulation system to the inlet weir 3, which extends across the entire width of the tank near one lower corner thereof. The liquid is then uniformly distributed to the tank, in a manner to be more fully described, and flows substantially parallel to the electrodes 4 toward the discharge openings 6, the height of the liquid being governed by means of suitable tubular valves (not shown) which are moved up and down within the openings 6, in accordance with prior practice.

My inlet weir 3 comprises a unitary removable structure of a number of plates or sheet members which are preferably galvanized or similarly treated to resist rust.

The main body member has a horizontal top surface 10 of approximately one-half the width of the tubular portion of the weir, a downwardly-inclined face 11 and, finally, a vertically-positioned member 12, the three surfaces 10-11 and 12 thus furnishing a suitable means for smoothly conducting the incoming liquid to the tank proper.

A vertical plate 13 is secured to a flange of the horizontal part 10 by means of a plurality of rivets 14, or otherwise, and is provided with a horizontal shelf member 15 that is spaced a predetermined distance

above the bottom of the tank and gradually tapers in width from the inlet end 17 to the closed farther end 18.

Thus, a slot or bottom opening 16, that gradually increases in width from the inlet end of the weir toward the other end, is formed.

A plurality of transversely-extending plates 19 are spaced within the weir along the slot 16 and of a length that gradually increases as the size of the slot increases, for a purpose to be set forth.

A further set of plate members 20 are spaced along the outer face of the vertical plate 13 in substantial alinement with the respective plates 19 and severally have their outer edges abutting against one end-wall of the rheostat tank 1. A plurality of base members, in the form of longitudinally-extending strips 21, are provided for the purpose of allowing the weir to rest upon the bottom surface of the tank.

The spacing of the inner transversely-extending plates 19 with respect to the slot 16 and the shelf 15 is such that the length of the plates varies substantially inversely with the size of the shelf, thereby tending to produce a substantially uniform efflux of liquid throughout the width of the tank, as hereinafter more fully explained. The plates 19 are suitably flanged and secured to the vertical plate member 13 by means of rivets 22, for example, and the free ends 23 of the plates 19 are bent against the direction of the incoming fluid to smoothly divide the stream into portions and divert such portions into the pockets between successive plates 19 with a minimum degree of eddies and resistance to the movement of the remaining part of the stream.

The vertically-extending plates 20 are suitably flanged and secured, by means of rivets 24, to the plate member 13, the lower corners of the plates 20 being cut away to allow a certain degree of diffusion of the various pockets of water during the spiral passage from the inside of the weir to the tank proper.

The base members or strips 21 may conveniently be integrally related to vertically-extending end members 25 which are secured to the respective end plates of the series of transversely-extending plates 19 and 20, respectively, by means of a plurality of rivets 26 and 27. Thus, the base members also serve to brace the transversely-extending plates and lend further rigidity to the structure.

Assuming that the inlet weir 3 is installed in one lower corner of the rheostat tank 1 in general alinement with the inlet pipe 2, the operation of the weir to produce a substantially uniform efflux of liquid throughout the width of the tank may be set forth

as follows: The incoming liquid has an initially high velocity head by reason of its discharge from the customary pump, for example, and, therefore, the static head of the liquid is substantially overcome at first, but gradually increases in effective value, as the velocity head decreases during the travel of the liquid toward the closed end of the inlet weir by reason of the interception or slicing off of portions of the stream by the successive transversely-extending plates 19. The function of the horizontally tapered plate member or shelf 15 is to hold up a gradually decreasing portion of the incoming stream and thus prevent it from immediately dropping to the bottom of the tank.

The successive plates 19, by intercepting the stream gradually nearer to its outer edge, that is, the edge nearest the plate 13, turn the intercepted portions at substantially right angles to the main stream direction and thus form pockets of liquid of gradually increasing size which drop through the corresponding portions of the slot 16 to the bottom of the tank. Since the quantity of liquid discharged in a unit of time is equal to the product of the area of the orifice multiplied by the unit velocity of the stream, in accordance with the well-known formula

$$Q = av,$$

it follows that the trapezoidal blocks of liquid in the various pockets between the successive plates 19 should increase in size directly with the decrease of the velocity head of the incoming main stream, or, stated another way, the area of the slot 16 gradually increases in size as the total static and kinetic pressures of the incoming stream that tend to expel the liquid from the weir gradually decrease, and thus the present arrangement of parts accomplishes the desired result of substantially equal efflux of liquid across the entire tank.

When the liquid has dropped through the slot 16 to the bottom of the tank, it rises between the successive pairs of outer transversely-extending plates 20, a certain amount of equalizing diffusion being permitted by reason of the cutting away of the lower corners of the plates 20, and thus flows over the top surfaces 10 and 11 of the weir structure substantially at right angles to the direction of the main inlet stream, that is to say, substantially parallel to the direction of the electrodes 4, as indicated by the arrows.

I have thus provided a compact unitary inlet-weir structure for insuring a substantially uniform efflux of liquid throughout the width of a rheostat tank, the distribution of liquid being accomplished in such

manner that the formation of harmful eddies is substantially obviated.

It will be appreciated that, in case a cylindrical inlet weir is employed, an equal spacing of the interior baffle-plates 19 and equal successive increases in the size thereof will not produce an equal efflux of liquid throughout the tank width, by reason of the different lengths of the intercepting chords. 10 However, the proper spacing to give the desired result may readily be calculated, as will be understood.

Reference may now be had to Fig. 3, which discloses a simple construction of the 15 general class under consideration for performing the desired function, although possibly not quite as effectively as the previously-described structure.

The device illustrated in Fig. 3 comprises 20 a tubular pipe or conduit 30 which extends from the inlet pipe 2 across the entire width of the rheostat tank 1 and is provided with a side opening or slot 31 that gradually decreases in size from the inlet end of the 25 pipe 30 to the closed end thereof.

A downwardly inclined apron member 32 extends from the top of the pipe 30 to the bottom of the rheostat tank to permit of a non-splashing entrance of liquid to the tank 30 proper.

A plurality of baffle-plates or barriers 33 are spaced suitable distances apart, along the outer sides of the pipe 30 near the tapered slot 31, thereby serving to effect the 35 upward movement of successive pockets of liquid, after they have been discharged from the tapered slot, over the apron member 32 to the rheostat tank, in substantially parallel paths at right angles to the direction 40 of the main incoming stream, thus serving a purpose similar to that set forth in connection with the previously-described plates 20.

In the present instance, the slot 31 is 45 tapered in the opposite direction from the slot 16 of Figs. 1 and 2, since no inner baffle-plates 19 are provided to materially decrease the velocity head of the incoming liquid and successively intercept portions 50 thereof. In the structure of Fig. 3, the incoming liquid rapidly flows toward the closed end of the pipe 30 where the stream tends to concentrate, thereby increasing the available static head, which static head 55 gradually decreases as the inlet end of the pipe is approached. Consequently, only a relatively narrow opening is necessary near the closed end of the pipe in order to effect the outflow of a quantity of liquid that is 60 equal to the quantity discharged from the inlet end of the pipe through the largest portion of the slot. The dimensions of the slot are, of course, designed to provide a discharge opening that varies along the 65 pipe substantially inversely with the varia-

tion of the static head, whereby substantially equal volumes of liquid are discharged between the successive pairs of baffle-plates 33 over the apron 32 to the rheostat proper.

It will be understood that, in place of the tapered slot 31, a single row or a number of rows of holes that gradually decrease in diameter may be drilled along the pipe 30.

I do not wish to be restricted to the specific structural details or arrangement of parts herein set forth, as various modifications thereof may be effected without departing from the spirit and scope of my invention. I desire, therefore, that only such 80 limitations shall be imposed as are indicated in the appended claims.

I claim as my invention:

1. A weir for liquid rheostats having longitudinally extending liquid-ejecting means 85 of gradually varying size.

2. A weir for liquid rheostats having a longitudinally-extending slot of a width that gradually decreases from one end of the 90 weir to the other.

3. A weir for liquid rheostats having a side opening of lesser size near the liquid-inlet end than near the other end of the 95 weir.

4. A liquid-rheostat weir of general tubular form adapted to receive liquid at one end and discharge it through a side opening of a width that gradually increases from the inlet end to the other end of the weir.

5. A weir for liquid rheostats having 100 longitudinally-located liquid-distributing means of gradually varying size and a plurality of transversely-extending means for successively partially intercepting the liquid flow.

6. A weir for liquid rheostats having longitudinally-located liquid-distributing means of gradually varying size and a plurality of transversely-extending plates that 110 gradually vary in size with the liquid-distributing means.

7. A weir for liquid rheostats having a longitudinally-extending slot of a width that gradually decreases from one end of the 115 weir to the other, and a plurality of transversely-extending plates for effecting a substantially equal efflux of liquid throughout the length of said slot.

8. A weir for liquid rheostats having a side opening of lesser size near the liquid-inlet end than near the other end of the 120 weir, and a plurality of transversely-extending plates spaced along said slot and of a size that varies substantially directly with the size of the slot, whereby a substantially equal efflux of liquid obtains throughout the length of said slot.

9. A liquid-rheostat weir of general tubular form adapted to receive liquid at one end and discharge it through a side opening 125

of a width that gradually increases from the inlet end to the other end of the weir, a plurality of transversely-extending plates spaced within the weir along said slot, and a plurality of other plates spaced along one outer side of the weir.

10. A liquid-rheostat weir of general tubular form adapted to receive liquid at one end and discharge it through a bottom opening of a width that gradually increases from the inlet end to the other end of the weir, a plurality of transversely-extending plates spaced within the weir along said slot, and a plurality of other plates spaced along 15 the opposite outer side of the weir in substantial alinement with the respective inner plates.

11. A liquid-rheostat weir of general tubular form adapted to receive liquid at one end and discharge it through a bottom opening of a width that gradually increases from the inlet end to the other end of the weir, a plurality of transversely-extending plates spaced within the weir along said slot and 20 of a size that varies substantially directly with the size of the slot, and a plurality of other practically identical plates spaced along the opposite outer side of the weir in substantial alinement with the respective inner plates.

12. In a liquid rheostat, the combination with a rectangular electrode-containing tank, of an inlet pipe communicating with the tank near one lower corner thereof, and a weir of general tubular form extending from said pipe across the tank and having a bottom surface spaced a predetermined distance above the tank bottom and provided with a slot that gradually increases in size from said pipe to the other side of the tank.

13. In a liquid rheostat, the combination with a rectangular electrode-containing tank, of an inlet pipe communicating with the tank near one lower corner thereof, and a weir of general tubular form extending from said pipe across the tank and having a bottom surface spaced a predetermined distance above the tank bottom and provided 45 with a slot that gradually increases in size from said pipe to the other side of the tank, and a plurality of transversely-extending plates spaced along one side of the weir and severally abutting against one side of the tank.

14. In a liquid rheostat, the combination with a rectangular electrode-containing tank, of an inlet pipe communicating with the tank near one lower corner thereof, and a weir of general tubular form extending from said pipe across the tank and having a bottom surface spaced a predetermined distance above the tank bottom and provided with a slot that gradually increases 60 in size from said pipe to the other side of

the tank, a plurality of transversely-extending plates spaced within the weir along said slot, and a plurality of other plates spaced along the opposite outer side of the weir in substantial alinement with the respective inner plates and severally abutting against one side of the tank. 70

15. In a liquid rheostat, the combination with a rectangular electrode-containing tank, of an inlet pipe communicating with the tank near one lower corner thereof, and a weir of general tubular form extending from said pipe across the tank and having a bottom surface spaced a predetermined distance above the tank bottom and provided with a slot that gradually increases in size from said pipe to the other side of the tank, and a plurality of transversely-extending plates spaced along one side of the weir and severally abutting against one side of the tank, and base members resting on the bottom of the tank. 80

16. In a liquid rheostat, the combination with a rectangular electrode-containing tank, of an inlet pipe communicating with the tank near one lower corner thereof, and a weir of general tubular form extending from said pipe across the tank and having a bottom surface spaced a predetermined distance above the tank bottom and provided with a slot that gradually increases in size from said pipe to the other side of the tank, a plurality of transversely-extending plates spaced within the weir along said slot, a plurality of other plates spaced along 95 the opposite outer side of the weir in substantial alinement with the respective inner plates and severally abutting against one side of the tank, and a plurality of spaced longitudinally-extending base members resting on the bottom of the tank. 100

17. A weir for liquid rheostats having a longitudinally-extending slot of a width that gradually decreases from one end of the weir to the other, and a plurality of external plates for directing successive portions of the liquid flow at substantially right angles to the direction of the incoming stream. 110

18. A weir for liquid rheostats having an inlet at one end, means for gradually varying the velocity head of the liquid in accordance with the distance from the inlet end, and lateral-discharge means for oppositely varying the time-volume of liquid to maintain a substantially constant liquid delivery 115 throughout the length of the weir.

19. A weir for liquid rheostats having an inlet at one end and a plurality of members for intercepting successively increasing volumes of incoming liquid and for simultaneously reducing the velocity head of the liquid. 125

20. A liquid-rheostat weir of general tubular form adapted to receive liquid at one end, and means for materially changing the 130

direction, and for simultaneously gradually reducing the velocity head, of the liquid.

21. In a liquid rheostat, the combination with an electrode-containing tank, of an inlet pipe communicating with the tank, and a 5 weir of general tubular form extending from said pipe across the tank and provided with means for gradually reducing the velocity head of the liquid in accordance

with the distance from the inlet end and 10 means for oppositely varying the time-volume of discharged liquid to maintain a substantially constant liquid delivery to the tank throughout the width thereof.

In testimony whereof, I have hereunto 15 subscribed my name this 24th day of Nov. 1916.

CHARLES C. WHITTAKER.
